United States Patent Office

Des. 179,133
Patented Nov. 6, 1956

179,133

BURGLAR ALARM OR SIMILAR ARTICLE

Richard A. Gordon, Freeport, N. Y.

Application May 17, 1956, Serial No. 41,524

Term of patent 14 years

(Cl. D72—1)

The figure is a perspective view of a burglar alarm or similar article, showing my new design.

I claim:

The ornamental design for a burglar alarm or similar article, as shown.

References Cited in the file of this patent
UNITED STATES PATENTS

D. 127,597	Wyatt	June 3, 1941
D. 148,109	Karrol	Dec. 16, 1947